UNITED STATES PATENT OFFICE

ROBERT L. SPRAGINS, OF ABERDEEN, MARYLAND
SMOKING APPLIANCE

Application filed April 9, 1930. Serial No. 442,853.

This invention relates to smoking devices and more particularly has reference to smoking pipes and cigar and cigarette holders.

This application is a continuation in part 5 of my copending applications, Serial No. 310,596 filed October 5, 1928; Serial No. 405,162, filed November 6, 1929, and Serial No. 406,333 filed November 11, 1929.

Upon smoking there is formed within the 10 bottom of a pipe bowl, a dirty gummy mass, and as is well known, the stem becomes contaminated with a liquid disagreeable to the taste, which is condensed from the tobacco smoke. Frequently on drawing through the 15 stem of the smoking device this liquid is injected into the smoker's mouth as well as solutions of particles of tobacco and saliva. The deposits of the product of the smoked tobacco tend to clog the stem of the pipe, 20 with the result that the dirty and disagreeable task of cleaning the smoking apparatus is necessitated at frequent intervals.

The difficulties encountered in smoking 25 pipes as outlined above are also present in the use of cigar and cigarette holders. In the case of the holder, while the bowl is eliminated, a stem through which the smoke is drawn into the smoker's mouth must be considered. This stem is subjected to clogging, similar to that outlined above, and as 30 in the case of a pipe requires frequent cleaning.

The art, while often providing smoking 35 devices with absorbing, adsorbing and filtering units, has failed to consider the possibilities of eliminating undesired vapor particles from the smoke by condensing them and so separating the condensed liquids that they can not reach the smoker's mouth.

40 While construction methods in the past have made use of a metallic tube inserted in the neck of the bowl so as to lead the smoke from the bowl to the mouth grip, because of the fact that metal is a good heat conductor, 45 and the tube is formed of a material having a thin cross section, it soon reaches a temperature which is substantially the same as the smoke which passes therethrough. As soon as this condition arises, it will be appreciated that condensation in the tube 50

ceases. Moreover, in constructions of this type the metal condensation tube is in direct communication with the mouthpiece of the smoking apparatus so that any liquids condensed therein are drawn into the smoker's mouth. 55

While attempts have been made to eliminate the disadvantages encountered in using the ordinary smoking devices such as pipes, 60 cigar and cigarette holders, they have been upon an elaborate and complicated scale with a consequent high expense. The majority of these developments have also been ineffectual to remove the inherent disadvantages in these devices. Moreover, nearly all of the 65 developments in smoking appliances which have to any extent eliminated the drawing of distasteful substances into the smoker's mouth have also operated to remove from the tobacco smoke the effect known to smoker's as the "kick". 70

The major object of this invention is to provide means to prevent distasteful substances and particles of tobacco from being 75 drawn into the mouth of the smoker, while at the same time allowing the many pleasing properties of the smoke to remain unaltered.

Another important object of this invention is to prevent any liquid introduced into 80 the stem of the smoking device from flowing into the smoking material receptacle associated therewith.

Another object of this invention is to devise smoking devices such as pipes, and cigar 85 and cigarette holders provided with readily detachable means, which will prevent distasteful substances from being drawn into the mouth of the smoker, and will operate 90 to cool the smoke and make the same pleasing to the smoker.

Yet another object of the invention is to provide a smoking device with a compartment entirely separated from the smoke passages wherein the filth and liquids formed 95 and/or injected into the apparatus are collected or accumulated.

Still another object of the invention is the designing of a novel two part mouthpiece for 100 a smoking device, the grip portion thereof

being formed of a relatively infusible organic compound, which encases a tubular moisture absorbing member having a substantially uniform diameter throughout its length.

A still further object of the invention is the provision of a two part mouthpiece having absorbing qualities adapted to prevent any moisture from reaching the mouth of the user, the inner part thereof being of a length sufficient to extend for a substantial distance within the stem of the smoking device.

Another object of the invention is to prevent any liquid introduced into the stem of the smoking device from flowing into the smoking material receptacle associated therewith.

A further object of the invention is to provide a smoking device provided with a stem having a novel condensation and drainage unit adapted to condense any vapor carried in the smoke and separate and collect the same therefrom.

With these and other objects in view which may be incident to my improvements, the invention consists in the parts and combinations to be hereinafter set forth and claimed, with the understanding that the several necessary elements comprising my invention may be varied in construction, proportions and arrangement without departing from the spirit and scope of the appended claim.

The invention comprehends the provision of a smoking device which allows the maximum enjoyment to the user. One method of practically effecting the concept of the invention is the provision of a smoking apparatus having a smoking material receptacle connected to a two compartment stem forming a condensation and drainage unit, and a mouthpiece provided with an absorbing member secured to the latter.

In order to make my invention more clearly understood, I have shown in the accompanying drawing, means for carrying the same into practical effect without limiting the improvements in their useful applications to the particular constructions which for the purpose of explanation have been made the subject of illustration.

In the drawing:

Figure 1 is a sectional view of a pipe constructed in accordance with my invention.

Figure 2 is a cross sectional elevation taken along the line 2—2 of Figure 1.

Figure 3 is a cross sectional elevation taken along the line 3—3 of Figure 1.

Figure 4 shows a sectional view of the invention embodied in a cigar or cigarette holder.

Figure 5 is a sectional elevation of a pipe similar to that shown in Figure 1 but provided with a different arrangement of the smoke passages positioned therein.

Figure 6 is a cross sectional elevation taken along the line 6—6 of Figure 5.

Figure 7 is a cross sectional view taken along the line 7—7 of Figure 5.

Throughout the drawing, like reference numerals refer to similar parts in the different views. There is shown in Figure 1 a sectional view of a smoking pipe having a bowl or smoking material receptacle 1, and a mouthpiece designated by 2 connected thereto by means of a tubular stem 3. The tobacco receiving bowl 1 may be of any desired shape and may be constructed of any suitable material. It may be observed that the bowl is provided with a neck 4, the end of which has formed thereon a reduced portion 5. A passageway 6, below the center line of the neck 4, extends through the neck and into the bowl 1.

From an inspection of Figure 1 it may be observed that the passageway 6 has a portion thereof enlarged and is adapted to receive a smoke duct or conduit 7, of considerable length. The purpose of the duct will herein-after appear. It is to be noted that the bore of the duct 7 is substantially the same as that of the passageway 6.

The tube 3 which forms the stem of the pipe is of such diameter that its end firmly engages the reduced portion 5 formed upon the end of the neck 4 of the smoking material receptacle. By this means the tube is secured to the smoking material receptacle because of its tight fit or engagement with the reduced portion.

Near the end of the tube 3 most distant from the smoking material receptacle there is provided a partition 8 which divides the tube into a forward compartment or chamber 9 and a rearward compartment or chamber 10. The partition is flush with the walls of the tube for its full periphery and may be formed integral therewith or secured thereto in any convenient manner. In Figure 1 the partition is disclosed as formed integral with the tube walls which upon the left of the partition possess a smaller cross section than on the right. While this formation of the tube walls tends to provide a structure possessing considerable strength, it will be appreciated that this practice may be varied if desired so that the walls of the tube 3 are of a uniform cross section throughout the full length of the tube.

For the purpose of providing communication between the compartments 9 and 10 the partition 8 is provided with two openings, one below the other. The upper opening is in alignment with the passageway 6 in the neck of the bowl and is of a diameter sufficient to allow the smoke duct 7 to pass therethrough with a tight fit. In the second opening, just mentioned, there is positioned a short conduit 11 which may be maintained in position by frictional engagement with the sides of the opening. The conduit 11, as may be observed, affords a direct commun-

cation between the rearward compartment 10, which as will presently appear forms a condensation chamber, and a forward chamber 9, which as will also appear provides a drainage chamber or a unit.

Shown associated with the smoking material receptacle and the tube 3 is a two part mouthpiece 2 formed of an outer or encasing portion which provides a grip piece 12 for the teeth of the smoker and a tubular moisture absorbing member 13 having a uniform outer diameter and a bore designated by 13'. The grip piece has an internal bore or passageway of uniform diameter which extends entirely therethrough and in which the member 13 is detachably secured by frictional engagement with the sides thereof. Provided upon the rear or smallest end of the grip are the usual flanges formed upon mouthpieces of smoking appliances of this type. The inner or forward end of the grip piece is provided with a reduced portion 14 of a diameter adapted to form a tight engagement with the rearward end of the tube 3 when the mouthpiece is inserted therein.

It may be noted when the pipe is fully assembled that the absorbing member 13 is of a sufficient length to extend for a substantial distance within the compartment 9. Moreover, as shown, the ends of the moisture absorbing member and the smoke duct overlap without touching or connecting with each other. By reason of this construction the length of the pipe may be considerably shortened, and the possibility of sucking liquids through the smoke duct into the moisture absorbing member is eliminated.

In Figure 5 there is shown a slight modification of the arrangement of the smoke passageways of the pipe of Figure 1. A neck similar to the neck 4 is formed upon the smoking material receptacle and provided with a reduced portion which has secured thereto a stem 30 similar in construction to the stem 3 of Figure 1. Secured to the opposite end of the stem 30 is a mouthpiece 20.

The neck of the smoking material receptacle is provided with a passageway extending therethrough, the longitudinal center line of which lies in a horizontal plane passing through the longitudinal center line of the neck but slightly to one side thereof. As in the case of Figure 1 this passageway has a portion thereof enlarged so as to receive a smoke duct or conduit 70 of a length sufficient to extend within the stem and to pass through a partition 80 formed therein. The partition 80 is also provided with an opening in which there is positioned a conduit 110 having a lip 110' in the forward compartment 90 formed in the stem by reason of the partition.

As in the case of Figures 1, 2 and 3 the mouthpiece 20 is provided with a grip portion 120 in which is detachably secured a

moisture absorbing member 130, a suitable passageway extending entirely through the grip being provided for the reception of the moisture absorbing member. This passageway is so positioned that the moisture absorbing member 130 may have its longitudinal center line in a horizontal plane passing through the longitudinal center line of the mouthpiece but slightly to one side of the mouthpiece center line. The construction just described is clearly shown in Figures 6 and 7 where the moisture absorbing member 130 is up on the left of the smoke duct 70. In Figure 6 the conduit 110 has been shown as positioned in the transverse center line of the stem. By this arrangement the ends of the smoke duct and the moisture absorbing member extending within the rearward compartment 100 may overlap each other. Moreover, if desired, the conduit 110 may be raised a considerable extent above the floor or bottom of the stem.

In the preferred embodiment of the invention the smoke ducts 7 or 70 are constructed of relatively thick glass. However, materials possessing characteristics similar to glass and which are also easily cleaned may be employed if desired. Such materials are for example, phenolic condensation products, hard rubber, amber, or other relatively infusible organic substances. In some instances the duct may be formed of aluminum or other metal having a thick cross section. This requirement of thick walls is essential in order to prevent the metal conduit from quickly reaching the temperature of the smoke passing therethrough and the cessation of condensation. Similar materials may be employed in the construction of the tube 3. In the construction of the stem, however, a phenolic condensation product is preferred because of the less likelihood of it being broken and its light weight.

The mouthpiece, that is the encasing grip portions 12 and 120 are formed of material possessing a relatively great hardness which at the same time has a smooth surface. Suitable materials for the construction of the mouthpiece are phenolic condensation products, hard rubber, amber or any combination of these desired.

The moisture absorbing members 13 and 130 encased by the grips 12 and 120 respectively are formed of a suitable porous and moisture absorbing material such as wood, either seasoned maple or seasoned briar being provided. By this construction the flavors which these woods impart to the smoke is obtained. While the moisture absorbing members have been described as being constructed by either briar or maple it is to be understood that other species of wood may be employed if desired without departing from the spirit of the invention.

It is evident that the advantages sought to

- be attained will be accomplished by this construction. Briefly the operation of the pipe comprises condensing any vapor carried by the smoke in the smoke duct and in the condensation chamber 10 or 100, separating the condensed liquids from the smoke in the condensation compartment, conducting these liquids to the drainage chamber or compartment 9 or 90 and drawing the substantially dry smoke through a mouthpiece unfavorable to condensation occurring therein.
- The smoking material receptacle is filled with tobacco or other smoking material and this is lighted in the usual manner. Upon the smoker drawing on the pipe the smoke will enter the rearward compartment 10 or 100. As previously mentioned the duct 7 or 70 and tube 3 or 30 are formed respectively of glass, and a phenolic condensation product or other similar materials. It should be noted that these members are formed with relatively thick walls. While the preferred substances used in the formation of these members may be poor heat conductors, their heat absorbing capacity due to their mass and the large surface or contact area which they present to the smoke will successfully effect the desired condensation of the vapor. Moreover it will be appreciated that these substances possess relatively high specific heats and because of the mass of the members which they form, there will be a substantial continual absorption of heat from the smoke during the whole time of a pipe smoking.
- It will be appreciated that the smoke ducts 7 or 70 are in no way connected with their mouthpieces and moreover since the moisture absorbing members 13 and 130 and the smoke ducts overlap each other, these members are out of coincidence with each other. The purpose of the expedient is obvious when it is considered that a smoker, upon drawing smoke into his mouth, will produce a suction effect within the condensation chamber. Upon such a force being created, the smoke, condensed liquids and products of the smoked tobacco or other material will be drawn through the duct, and by reason of gravity, the latter will be deposited within the condensation chamber where they cannot be drawn into the mouthpiece. It is equally apparent that liquid injected, by the smoker, into the condensation chamber cannot reach the bowl because there is no connection between the duct 7 or 70 and the mouthpiece and because these parts are out of alignment with each other.
- While a certain amount of condensation occurs within the smoke duct it will be well understood that this amount is small when compared to that occurring in the condensation chamber proper. The smoke, after passing through the smoke duct, enters into the condensation chamber, where a further and

substantially complete condensation of the vapor carried thereby, occurs.

Any liquid in the condensation chamber, will when the pipe is held in a position with its bowl below the horizontal be conducted through the conduit and into the drainage chamber where it is collected. Should the pipe be held in a position so that the bowl is above the horizontal it may be observed that liquid from the condensation chamber is prevented from entering the moisture absorbing member because of its position and also because of the fact that it is unconnected with the conduit. The liquids and filth accumulated in the drainage chamber are substantially prevented from re-entering the condensation chamber because of the position of the conduit connecting these two compartments. In both Figures 1 and 5 the conduit connecting the forward and rearward compartment is elevated above the floor or bottom of the pipe stem a sufficient distance to prevent the liquid separated in the drainage unit from seeping back into the condensation chamber. Thus these liquids and filth are entirely separated from the smoke passages and cannot come into communication with them. It will be appreciated that any liquids of this nature coming in contact with the portion of the moisture absorbing member extending within the condensation chamber would be absorbed because of the absorption characteristics of the material forming it.

The smoke in a substantially dry condition is drawn from the condensation chamber through the tubular moisture absorbing member directly into the smoker's mouth. It has been pointed out that the moisture absorbing member is constructed of wood. While such a substance possesses a relatively high specific heat the mass of the member formed therewith is small, and moreover the other factor favorable to the occurrence of condensation, namely a large contact area for the smoke within the moisture absorbing member is lacking. This is apparent upon considering the bore area of the moisture absorbing member and it will hence be well understood that substantially no condensation occurs therein. Condensation in the bore of the moisture absorbing member is further limited by the fact that the smoke passing therethrough is in a substantially dry condition since by condensation in the chamber 9 practically all of the condensable vapors carried thereby have been removed.

Should, however, any condensation occur within the absorbing member, its absorbing qualities will take care of such and will prevent any liquid formed thereby from reaching the mouth of the smoker. The moisture absorbing member also to a certain extent, absorbs moist vapor carried in the smoke.

In the use of smoking devices, saliva is

sometimes ejected through the mouthpiece and into the stem of the pipe. Upon the 5 smoker drawing on the pipe, this saliva with some of the liquids condensed from the tobacco smoke are drawn into the smoker's mouth. The construction shown in my invention eliminates the possibility of this effect occurring. This is obvious upon considering the absorption qualities of the moisture 10 absorbing member. Any excess of fluid of this nature will be ejected into the condensation chamber, and by reason of gravity will fall to the lower portion thereof. When the pipe is held in the usual position so that the 15 bowl is below the horizontal and the mouthpiece is above the horizontal, fluid of this nature will run through the conduit 11 or 110 into the drainage chamber. However, when the pipe is held so that its bowl is elevated, the position and construction of the moisture 20 absorbing member within the condensation chamber, as previously pointed out, will prevent liquids flowing into the mouthpiece from the condensation chamber while the construction and placing of conduits 11 or 25 110 prevents liquids from flowing from the drainage chamber into the condensation chamber.

When it is desired to clean the pipe, the 30 mouthpiece is removed from the stem by exerting a force directed away from the bowl of the device. This results in freeing the mouthpiece entirely from the smoking apparatus. It should be noted that the moisture 35 absorbing members are constructed so as to be removable from their encasing members or its grip pieces. The moisture absorbing member may thus be permitted to dry out while a new member is inserted in its place and used therefor. Having removed the 40 mouthpiece the stem or tube may be readily detached from the neck of the material receptacle in a similar manner.

The tubes 3 and 30 and the smoke ducts 45 7 and 70 are formed respectively of a phenolic condensation product and glass, both of which materials lend themselves to easy cleansing. Both the smoke duct and the conduit 11 or 110 may be easily removed from the stem after the latter is detached from the smoking material receptacle. In the assembling of these parts, it is apparent that the reverse operations are gone through. Obviously in the construction shown, cleansing 55 operations need be undertaken only at infrequent intervals, particularly when the moisture absorbing member is frequently changed.

In Figure 4 the smoking device is embodied 60 in a cigar or cigarette holder having similar construction details, indicated by the primed reference numerals, as the form of the device shown in Figures 1 through 3. A modified 65 form of smoking material receptacle 15

adapted to receive the end of a cigar or cigarette is associated with a tubular stem 3' which engages a reduced portion 16 formed upon the end of the receptacle. Detachably secured to the opposite end of the stem 3' is a 70 two part mouthpiece 2' provided with a moisture absorbing member 13''. As in the case of the apparatus shown in Figure 1, a bore 6' extending through the smoking material receptacle is employed. Mounted in the bore 6' is the smoke duct 7' which extends through the forward compartment 9', through the partition 8' and into the rearward compartment 10'. It should be noted that the partition 8' is 75 provided with three openings, one at its center in alignment with the bore 6' and the other openings formed at the top and bottom of the partition as shown in Figure 4. In these openings there is positioned a conduit 17 and a conduit 18. Also to be noted is the fact that the end of the smoke duct 7' is suitably curved at 19 so as to allow it to overlap the end of the moisture absorbing member 13''. As is well known holders of this type 80 are rarely ever held in the same position. Hence two conduits, namely 17 and 18 are employed for conducting the condensed liquids into the drainage compartment 9', the conduit 17 being at the lower part of the partition and the conduit 18 being at the upper part of the partition as shown in Figure 4. By the use of the two conduits, drainage from the compartment 10' into the compartment 9' is assured. 85

While the modification in Figure 5 has been shown applied to a pipe, it will be appreciated that it could be readily formed into a cigar or cigarette holder similar to that shown in Figure 4 by merely providing a smoking material receptacle corresponding in nature to that of the receptacle 15. 90

In the operation of the cigar and cigarette holder, one end of the cigar or cigarette is inserted within the receptacle 15 and the opposite end is lighted in the usual manner. It is apparent that the smoke, uncondensed vapors and condensed liquids will be carried through the smoke duct and into the condensation unit where the latter will be deposited in the manner previously described. Moreover the uncondensed vapor will here be subjected to a further condensation effect. By using the construction previously described in connection with Figure 1 or Figure 5 it will be apparent that liquid within the condensation unit is prevented from reaching the mouthpiece as well as the smoking material receptacle in any position in which the holder may be held. Likewise it may be observed that this construction maintains the separated liquids in the drainage chamber and substantially prevents them from re-entering the condensation chamber. By the use of the moisture absorbing mouthpiece, 110 115 120 125

heretofore described, the user of the holder is assured of a cool and dry smoke.

From the foregoing description it will be appreciated that I have provided a novel 5 smoking device having a novel condensation and drainage unit as well as a novel mouthpiece which effectively prevents any liquid in the smoking material receptacle from reaching the mouth of the smoker. It may 10 also be realized that I have devised a smoking device capable of preventing liquid injected by the smoker into the mouthpiece thereof from reaching the smoking material receptacle. Likewise it is to be observed that 15 the smoking apparatus previously described is applicable to pipes as well as cigar and cigarette holders, and in both instances provides a cool and dry smoke affording the maximum pleasure to the user's taste. Besides 20 being of inexpensive construction the device possesses a simple design facilitating quick and thorough, although infrequent cleansing of the parts thereof.

While I have shown and described the preferred embodiment of my invention, I wish it 25 to be understood that I do not confine myself to the precise details of construction herein set forth, by way of illustration, as it is apparent that many changes and variations 30 may be made therein by those skilled in the art, without departing from the spirit of the invention, or exceeding the scope of the appended claim.

I claim:

25 In a smoking apparatus comprising a smoking material receptacle, a tubular stem detachably secured thereto, a two part mouthpiece detachably secured to said stem, a partition provided within said stem and 30 dividing it into two compartments, said partition being provided with a plurality of openings, a smoke duct connected to said smoking material receptacle and extending through the forward compartment, partition, and into the rearward compartment, said mouthpiece having an encasing grip piece and an encased moisture absorbing member detachably secured therein, said moisture absorbing member extending entirely through the grip piece and being of a 35 length sufficient to extend within the rearward compartment of said stem, the end of said moisture absorbing member overlapping the end of said smoke duct, and a conduit 40 providing a passageway between the two compartments positioned within an opening of said partition.

In testimony whereof I affix my signature.
